Primary Examiner — Gino Colan(74) *Attorney, Agent, or Firm* — Kirk A. Buhler; Buhler & Associates Patenting(57) **CLAIM**

The ornamental design for a ladder half-step, as shown and described.

DESCRIPTION

FIG. 1 is a top perspective view of a ladder half-step, showing my new design;

FIG. 2 is a top plan view thereof;

FIG. 3 is a bottom view thereof;

FIG. 4 is a right-side elevation view thereof;

FIG. 5 is a left side elevation view thereof;

FIG. 6 is a left side sectional view taken along lines **6-6** from FIG. 2 thereof;

FIG. 7 is a front elevation view thereof;

FIG. 8 is a rear elevation view thereof;

FIG. 9 is a front sectional view taken along lines **9-9** from FIG. 3 thereof; and,

FIG. 10 is a top perspective view shown in an environment of use.

The broken lines in FIG. 10 depict environmental subject matter and form no part of the claimed design.

The broken lines shown in the figures are for the purpose of illustrating portions of the ladder half-step and form no part of the claimed design.
